Primary Examiner — Catheri Oliver-Garcia(74) *Attorney, Agent, or Firm* — Sheridan Ross P.C.(57) **CLAIM**

The ornamental design for a sling carrying bag, as shown and described.

DESCRIPTION

FIG. 1 is a front perspective view of the sling carrying bag;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof; and,
FIG. 7 is a bottom plan view thereof.
The broken lines depict environmental structure and do not form part of the claimed design.
